US00D631455S

(12) **United States Design Patent**
Kim et al.

(10) **Patent No.:** **US D631,455 S**
(45) **Date of Patent:** **** Jan. 25, 2011**

(54) **MOBILE PHONE**

(75) Inventors: **Joon-Suh Kim**, Anyang-si (KR); **Naoki Shimada**, Ranchos Dominguez, CA (US)

(73) Assignee: **Samsung Electronics Co., Ltd.**, Suwon-Si (KR)

(**) Term: **14 Years**

(21) Appl. No.: **29/361,483**

(22) Filed: **May 12, 2010**

(30) **Foreign Application Priority Data**

Mar. 26, 2010 (KR) 30-2010-0013348

(51) **LOC (9) Cl.** **14-03**

(52) **U.S. Cl.** ..... **D14/138 AB; D14/138 G**

(58) **Field of Classification Search** ..... D14/138 AA, D14/496, 341, 345, 346, 203.3, 203.4, 203.7, D14/138 AD, 138 R, 138 AB, 138 G; 455/575.1, 455/556.2, 575.3; D21/517; 379/433.01, 379/433.04, 433.13

See application file for complete search history.
